UNITED STATES PATENT OFFICE.

LEWIS WOLFLEY, OF PRESCOTT, ARIZONA TERRITORY.

DUMP-BUCKET.

No. 910,253.

Specification of Letters Patent.

Patented Jan. 19, 1909.

Application filed August 19, 1907. Serial No. 389,256.

To all whom it may concern:

Be it known that I, LEWIS WOLFLEY, a citizen of the United States, residing at Prescott, in the county of Yavapai and 5 Territory of Arizona, have invented certain new and useful Improvements in Dump-Buckets, of which the following is a specification.

My invention relates to buckets or receptacles for lowering materials and depositing or dumping them in a suitable manner, especially automatically, and has for its principal object the production of such a device particularly adapted for use in the 10 formation of concrete piling, although it will obviously be useful for other purposes and in other connections.

The invention resides in the novel construction and arrangement of parts of an 15 automatic dump bucket hereinafter described and claimed, and illustrated in the accompanying drawings, in which—

Figure 1 is a view in side elevation of the bucket closed, the movable part being shown 20 open, by dotted lines; Fig. 2 is a similar view of the same, looking from left to right in Fig. 1; Fig. 3 is a plan view in section taken on line 3—3, Fig. 1; and Figs. 4 and 5 are enlarged details of the latch.

Referring to the drawings, A is the main 25 body portion of the bucket, and B the lower portion. Body portion A has a diameter which increases from top to bottom, or, in other words, its walls slope outwardly and 30 downwardly, so that the material contained in this portion will be readily discharged when released. The bucket is connected to a hoisting rope or chain in any suitable way, as by bail a.

The lower portion B is composed of sections, one at least of which is movable. I 35 have shown these sections as two in number, section b being rigidly attached to body portion A, and section b' being movably connected to the body portion by hinge b². The walls of the lower section B preferably 40 slope inwardly, the angle of slope of section b' being less than that of section b. Braces or holding clips a'—a² are provided upon 45 body portion A to hold the outer corners of section b' against the strain of the load.

Lower portion B is normally held closed 50 by a latch member C pivoted at c for vertical movement upon one of the sections, as 55 b, and is provided with a latch piece c' which engages a slot c² in the nose piece

c³ of the other section. Latch member C also has a trip finger c⁴ which extends downwardly beyond the end of the bucket and is adapted to contact with the surface or 60 material at the end of the downward travel to release the latch and dump the bucket. Finger c⁴ has a rearward clip c⁵ to brace the parts when the latch is closed.

The operation of the bucket will be obvious from the drawing and foregoing description. The section b' being in its closed position, as shown in Figs. 1 and 2, latch member C is moved to its latching position (shown in Fig. 1, and in whole lines in Fig. 2), latch piece c' engaging the slot c² in nose piece c³ and thereby securely maintaining section b' closed. When, in lowering the bucket, trip finger c⁴ strikes the ground or material already deposited, latch member C 70 is moved to the position shown by dotted lines in Fig. 2, and hinged section b' swings to the position shown by dotted lines in Fig. 1. Owing to the taper of main body portion A of the bucket, the contained material is 75 readily discharged, and is not obstructed by lower portion because of the shape and arrangement of the parts.

As this bucket is particularly designed 80 for lowering mortar into tubes or casings to 85 form concrete piles, it is preferably made round in plan outline; and it will be seen that section b slopes sufficiently to protect latch member C from contact with the tube or casing. It will also be observed that nose 90 piece c³, in addition to coöperating with latch piece c', protects the lower ends of the sections b, b', from injury by contact with the ground or previously deposited material.

It will of course be understood that my 95 improved bucket may be used for raising, or lowering and dumping any divided or granular material, such as broken stone, coal, etc., and that modifications may be made in the details and parts shown and described without departing from the invention.

Having thus described my invention, what I claim as new and desire to secure by Letters Patent is:

1. In a dump bucket, a main body portion 105 having an internal diameter increasing from top to bottom, a lower portion having a section movable relatively to said body portion, and means for latching said section.

2. In a dump bucket, a main body portion 110 tapering from bottom to top, a lower portion having a hinged section movable relatively

to said body portion, and means for latching said section.

3. In a dump bucket, a main body portion, a lower portion having a section fixed 5 with respect to the main body portion and sloping toward the center axis of the bucket, a hinged section also sloping toward said axis and co-operating with said fixed section, and means for latching said hinged 10 section.

4. In a dump bucket, a main body portion the walls of which are fixed, a lower portion, the walls of which slope toward the center axis of the bucket and consist of sections 15 of which one at least is movable with respect to the body portion for dumping, and a latch for connecting said sections.

5. In a dump bucket, a main body portion, the walls of which are fixed and slope 20 outwardly and downwardly, and a lower portion, the walls of which slope inwardly and downwardly and consist of sections of which one at least is movable with respect to the body portion for dumping.

25 6. In a dump bucket, a main body portion, a lower portion comprising sections of which one at least is movable, a latch member pivoted to one section and engaging a lip on the other section, and a finger extending from said latch member below the end 30 of said sections to engage a stop and open the latch.

7. In a dump bucket, a body portion, a lower portion comprising sections of which 35 one at least is movable, a latch member comprising a bar having a lateral extension pivoted to one section and engaging a lip on the other section, the forward end of said bar constituting a trip finger and the rear- 40 ward end lying close to the section, and a

clip upon said section under which said rearward end of the bar slides when the parts are in the latched position.

8. In a dump bucket, a main body portion, a lower portion comprising sections of 45 which one at least is movable, a latch member pivoted to one section for vertical movement and engaging a lip on the other section, and a finger extending downwardly from said latch member to engage a stop 50 and release said movable section.

9. In a dump bucket, a main body portion, the walls of which slope outwardly and downwardly, a lower portion the walls of which slope inwardly and downwardly 55 and consist of sections, one at least of which is movable, and a latch arranged to engage a stop and release said movable section at the end of the downward travel of the bucket.

60 10. In a dump bucket, a main body portion, a lower portion comprising a fixed and a movable section sloping inwardly and downwardly, said movable section having a slope less than that of said fixed section 65 and extending across the center axis of the bucket, and means for latching said movable section.

11. In a dump bucket, a main body portion flaring downwardly to facilitate discharge of the contents, a lower dumping section hinged to said body portion, and a latch for said dumping section.

In testimony whereof I affix my signature, in presence of two witnesses.

LEWIS WOLFLEY.
